(Cl. 179—171)

response curve, either the primary, the secondary, or both are loaded by one or more resistors. I have discovered that by properly loading either a single amplifier stage or successive amplifier stages, the selectivity characteristic of the amplifier is not greatly changed by changes in bias produced by the A. V. C. circuit.

Other objects, features and advantages of my invention will appear from the following description when taken in connection with the accompanying drawings in which:

Figure 1 is a circuit diagram of one embodiment of my invention;

Figures 2, 3 and 4 are curves and circuit diagrams which are referred to in explaining my invention;

Figure 5 is a circuit diagram showing another embodiment of my invention;

Figure 6 is a pair of curves and a circuit diagram which are referred to in explaining another embodiment of my invention, and

Figure 7 is a circuit diagram of still another embodiment of my invention.

My invention will best be understood by referring first to Figures 2, 3 and 4. In Figure 2 the curve *a* is a selectivity curve for the tuned intermediate frequency transformer indicated at 1. This transformer has its primary loaded by means of a shunting resistor 2 whereby the selectivity curve is made flat-topped. The curve *a* represents the selectivity characteristic of the I. F. transformer when the capacity *C*₁ is included in shunt to the transformer secondary. The capacity *C*₁ is present in all amplifiers because of the input capacity of the amplifier tube. If the capacity *C*₁ is removed, as by making the control grid of the amplifier tube more negative for the purpose of reducing the gain of the amplifier and thereby reducing the input capacity, the selectivity curve of the I. F. transformer *1* is as shown by the curve *b*. If two such stages are connected in cascade, their overall selectivity is as shown by the curve *c*. Obviously such a selectivity characteristic is undesirable as it accentuates the high frequencies.

It will be apparent that the operation of an A. V. C. circuit in the above-mentioned type of receiver will tend to detune the I. F. amplifier. It is an object of my invention to provide an improved television or short wave radio receiver of the type having either manual or automatic volume or gain control.

More specifically, it is an object of my invention to provide an improved high frequency amplifier so designed that its gain may be varied according to its selectivity characteristic.

Figure 3, the curve *a* is the selectivity characteristic of the I. F. transformer *1* having a capacity *C*₁ in shunt to the secondary.

I claim as my invention:

1. A variable gain band pass amplifier stage comprising a transformer having a primary and a secondary, said primary and secondary being so tuned and coupled as to have a double peaked selectivity characteristic in the absence of loading on the transformer, an amplifier tube having a plurality of electrodes including input electrodes, means for coupling said secondary across said input electrodes, means for varying the direct current potential applied to one of said electrodes whereby the gain of said amplifier stage may be controlled, and means for so resistively loading both said primary and said secondary that the selectivity characteristic of said tuned transformer is substantially flat-topped, said primary and said secondary being resistively loaded unlike amounts, the ratio of primary loading to secondary loading being such that said selectivity characteristic remains substantially flat-topped during changes in said direct current potential.
2. The invention according to claim 1 characterized in that the ratio of one of said loadings to the other of said loadings is less than 3 to 1 and greater than 1 to 1.

3. The invention according to claim 1 characterized in that the ratio of one of said loadings to the other of said loadings is of the order of 2 to 1.

4. A variable gain band pass amplifier stage comprising a transformer having a primary and a secondary, said primary and secondary being so tuned and coupled as to have a double peaked selectivity characteristic in the absence of loading on the transformer, an amplifier tube having input electrodes, means for coupling said secondary across said input electrodes, means for varying the direct current potential between the input electrodes of said tube whereby the gain of said amplifier stage may be controlled, and means for so resistively loading both said primary and said secondary that the selectivity characteristic of said tuned transformer is substantially flat-topped, said primary and said secondary being resistively loaded unlike amounts, the ratio of primary loading to secondary loading being such that said selectivity characteristic remains substantially flat-topped during changes in said direct current potential.
